UNITED STATES PATENT OFFICE.

JOHN F. HEMENWAY, OF NEW YORK, N. Y.

PRESSURE-RELEASE FOR CLOTHES-WRINGERS.

1,322,437.

Specification of Letters Patent. Patented Nov. 18, 1919.

Application filed May 9, 1917. Serial No. 167,493.

To all whom it may concern:

Be it known that I, JOHN F. HEMENWAY, a citizen of the United States, residing at New York city, in the county of New York 5 and State of New York, have invented certain new and useful Improvements in Pressure- Releases for Clothes-Wringers, of which the following is a specification, reference being had therein to the accompanying 10 drawing.

This invention relates to a combined automatic and manual pressure release for clothes wringers, the object being to provide a release which is so constructed that the 15 same can be readily installed on the ordinary construction of clothes wringers now in use.

Another object of my invention is to provide a pressure release in which the automatic releasing bars are disposed on the inside of the frame above the shaft of the upper pressure roll in such a manner that they are operated by the upward movement so as to release the pressure retaining means 25 on the abnormal separation of the rolls.

Another object of my invention is to provide a clothes wringer having pivoted latches for holding the pressure means in predetermined position, said latches having 30 a connection with the manually operated means and the automatically operated means in order to allow the latches to be moved in position to release the pressure means by the manually operated means in case the 35 automatic means fails to operate.

Other and further objects and advantages of the invention will be hereinafter set forth and the novel features thereof defined by the appended claims.

40 In the drawings,

Figure 1 is a side elevation of a clothes wringer partly in section showing the application of my improved construction of pressure release thereto;

45 Fig. 2 is a perspective view of a portion of the pressure releasing mechanism detached; and

Fig. 3 is a detail elevation partly in section.

50 Like numerals of reference refer to like parts in the several figures of the drawing.

In carrying out my invention I employ a clothes wringer of the ordinary construction having the usual side bars 1 connected together by cross bars 2, the side bars being preferably formed slotted, in the upper ends

of which are slidably mounted a top bar 3 provided with threaded boxes 4 carrying pressure screws 5.

Mounted in the lower portions of the slotted side bars 1 of the wringer frame are bearings carrying pressure roll shafts 6 and 7, provided with pressure rolls 6', 7', the bearing of the upper pressure roll being provided with spring supports on which are mounted coil pressure springs 8 which are engaged by bearing plates 9 carried by a pressure bar 10. The bearing plates 9 are adapted to be engaged by the pressure screws 5 for adjusting the tension on the pressure rolls. 70

Secured to the side bars 1 of the wringer frame are slotted plates 11, provided with bearings 12 in which are pivotally mounted latches 13 adapted to be seated within recesses 14 formed in the ends of the top bar 75 3 so as to hold said top bar in predetermined position within the wringer frame in order to allow the pressure screws to be adjusted for adjusting the pressure means. The latches 13 are provided with laterally extending slotted arms 15 which extend through the slots formed in the plates 11 and through which the pressure screws 5 pass as clearly shown in Fig. 1.

In order to provide means for moving 85 the latches outwardly out of engagement with the top bar to release the pressure means automatically, I provide a pair of releasing bars 16 which are slidably mounted on screws 17 carried by the side bars 1 of the wringer frame and are provided with forked upper ends 18 which are slidably connected to the arms 15 as shown at 19, said releasing bars being adjusted in respect to the shaft 7 of the upper pressure 90 rolls 7' so that the bars will be raised by the passage of an abnormal thickness of goods through the pressure rolls. As the bars 16 are raised the latches 13 are swung outwardly on their pivots so as to release 95 the top bar, the movement of which is limited by the arms 15 working in the slots of the plates 11. As the top bar moves upwardly the pressure on the pressure rolls is released, and it will be seen that by this 100 construction when an abnormal thickness of goods or the operator's fingers are drawn between the pressure rolls, the pressure is instantaneously released.

The top bar of the frame is provided with 110 a centrally disposed bore in which is slidably mounted the shank 20, of a push but-

ton 21 which carries stud pins 22 at its lower end on which are slidably mounted the slotted arms 23 of forked levers 24 which are pivotally mounted in brackets 25 so 5 that when the push button is forced downwardly, the levers 24 will be rocked on their pivots. The shank of the push button is surrounded by a coil spring 26 for returning the same to normal position after it has 10 been depressed.

The free ends of the levers 24 are slidably connected to the free ends of the arms 15, of the latches 13, so that when the levers are rocked on their pivots by the downward 15 movement of the push button, the latches will be thrown outwardly out of contact with the top bar to release the pressure means. In the construction herein shown I show the connection between the pivoted levers 20 24 and the arms 15 in the form of a loose connection as the free ends of the levers 24 are provided with forked portions 24' which embrace the rounded end bars 15' of the slotted arms 15. It is, of course, understood that the ends of the arms and the levers could be bent around the bar 15' so as 25 to form a positive connection between the levers and arms without departing from the spirit of my invention, and I do not wish 30 to limit myself to any particular manner of connecting the arms and the latches to the operating levers.

From the foregoing description it will be seen that I have provided a clothes wringer in which a movably mounted top bar is held in predetermined position by pivoted latches having slotted arms extending around the pressure screws carried by the top bar and having a connection with 35 the manually operated means and the automatically operated means so that the pressure can be released by either of said means instantaneously.

I claim:

45 1. A clothes wringer, comprising a frame having pressure rolls and pressure means for said rolls mounted therein, a top bar movably mounted in said frame having pressure screws for adjusting said pressure 50 means, plates carried by the side bars of said frame, pivoted latches mounted in said plates engaging said top bar for holding said top bar in predetermined position within said frame, said latches being provided 55 with inwardly projecting apertured arms through which the pressure screws extend, and releasing bars arranged on the inner faces of said side bars slidably connected to the arms of said latches at their upper ends,

said bars being mounted in the path of travel of the pressure rolls and adapted to be operated thereby on the abnormal separation thereof.

2. A clothes wringer, comprising a frame having pressure rolls and pressure means 65 for said rolls mounted therein, a top bar movably mounted in said frame having pressure screws for adjusting said pressure means, slotted plates secured to the side bars of said frame, pivoted latches carried 70 by said plates for holding said top bar in predetermined position within said frame, apertured arms carried by said latches extending through the slots of said plates and through which the pressure screws extend, 75 and releasing bars operated by the abnormal separation of said rolls having a connection with said arms.

3. A clothes wringer, comprising a frame having pressure rolls and pressure means for 80 said rolls mounted therein, slotted plates secured to the side bars of said frame, pivoted latches mounted on said plates engaging said top bar for holding said top bar in predetermined position within said frame, apertured arms carried by said latches extending through the slots of said plates under said top bar, pressure screws carried by said top bar extending through the apertures of said arms for adjusting 85 said pressure means, and releasing bars operated by the abnormal separation of said pressure rolls having a connection with said arms.

4. A clothes wringer, comprising a frame 95 having pressure rolls and pressure means for said rolls mounted therein, a top bar movably mounted in said frame, slotted plates carried by the side bars of said frame, pivoted latches carried by said plates engaging 100 said top bar for holding said top bar in predetermined position within said frame, apertured arms carried by said latches extending through the slots of said plates under said top bar, pressure screws 105 carried by said top bar extending through the apertures of said arms, levers pivotally supported by said top bar having a sliding connection with the arms of said latches, and a spring actuated push button slidably 110 connected to said levers.

In testimony whereof I hereunto affix my signature in the presence of two witnesses.

JOHN F. HEMENWAY.
